UNITED STATES PATENT OFFICE.

ELMER M. JONES, OF ATLANTA, GEORGIA, ASSIGNOR TO JONES SIGNAL SYSTEM COMPANY, OF ATLANTA, GEORGIA, A CORPORATION OF GEORGIA

AUTOMATIC STOP OR CAB SIGNAL DEVICE.

1,142,886.

Specification of Letters Patent. Patented June 15, 1915.

Application filed April 8, 1912, Serial No. 689,211. Renewed November 13, 1914. Serial No. 872,052.

To all whom it may concern:

Be it known that I, ELMER M. JONES, a citizen of the United States, residing at Atlanta, Georgia, have invented a certain new and useful Improvement in Automatic Stops or Cab Signal Devices, of which the following is a full, clear, and exact description, reference being had to the accompanying drawings.

10 The object of this invention is to provide a simple and effective mechanism for controlling trains or cars as they pass given points along the track. The mechanism operates on the principle of invariably initiating the application of a brake or danger signal whenever a track device is passed, and then, if track conditions warrant it, counteracting such application before it becomes effective, otherwise allowing it to become effective. Reference should be made to my prior Patent No. 1,129,201 issued February 23, 1915, for broad dominating claims on the combination of instrumentalities for performing such operation. The present invention provides a different, and, in some ways, simpler form of mechanism for carrying out such operation. To that end I provide in the present invention at intervals along the trackway, normally stationary ramps which operate on vehicle mechanism to open an air valve; and I arrange these ramps so that they may be moved to a safety position, where they not only open the air valve but operate on vehicle mechanism to immediately close it. The invention includes both the ramp, or ground device, so arranged, and also the vehicle equipment designed to coöperate therewith.

40 In the drawings, Figure 1 is a side elevation, partly sectional, of the ground device. Fig. 2 is a sectional side elevation of the locomotive equipment. Fig. 3 is a vertical transverse section of the same, as indicated by the line 3—3 of Fig. 2.

45 Referring first to Fig. 1, 10 indicates one of the rails and 11 the ties of the trackway. 12 is the base plate of the ramp, or ground device, mounted on the projecting ends of the ties outside of rail 10. Rising from this base are ears 13 and 14. Jounaled in the ear 13 is a rock shaft 15, on which is a rock arm 16. This rock arm is hinged at 17 to a bar 18, which is slidably guided at 19 on the ear 14. The bars 16 and 18 are normally held in position shown, and thus constitute

a normally stationary ramp, which coöperates with vehicle mechanism, to be herein-after described, to open the air valve.

To hold the bars 16 and 18 normally stationary, and at the same time allow them to be depressed, should some obstruction on the vehicle require it, I support the joint of these bars by a stiff spring 20. This spring is mounted in a box or casing 21, secured to the under side of the frame 12. The spring 65 acts upwardly on a shoulder 23 on the plunger 24, at the upper end of which is a roller 25, bearing against the under sides of the bars 16 and 18 at their joint.

Fig. 1 shows in dotted lines an elevated 70 position of the ramp, and in such position it is adapted to not only open the air valve on the vehicle, but immediately close it, as hereinafter explained. To raise the ramp into this safety position, it is only necessary 75 to rock the rock shaft 15. I have shown in Fig. 1, a rock arm 30 on the rock shaft, connected by a link 31 with a semaphore blade 32 on a suitable staff 33. Accordingly, the rocking of the shaft 15 may not only raise 80 the ramp to safety position, but may simultaneously lower the blade to safety position. Obviously, the ramp mechanism may be connected with any semaphore mechanism, and the motive power which operates the blade 85 may raise the ramp.

Figs. 2 and 3 show a convenient form of locomotive equipment, designed to co-act with a ramp of the type shown in Fig. 1. In these views, 40 indicates or designates the 90 casing of an air valve having a seat 41. 42 is the plug for such seat, which has a stem 43, loosely socketed in the plunger 44, which is slidably mounted in the casing 40. A compression spring 45 surrounds the stem 95 43, between the head of the stem and a shoulder of the plunger. Accordingly, the spring tends to maintain the plug on the seat. This spring is stronger than the force of the air on the opposite side of the plug. 100

The valve plug is normally maintained on its seat by reason of the plunger 44 normally abutting the end 50 of a lever 51, which is pivoted at 52 in a vertical slide bar 53. This bar carries at its lower end a 105 roller 54. The lever 51 extends downwardly below the pivot 52, and carries a small roller 56, operating against the roller 54 on an opposite side from the head 50. Accordingly, the two rollers 54 and 56 co-act to 110

hold the lever 51 against swinging on its pivot. The bar 53 is normally held in its lowermost position by a compression spring 60 engaging its upper end.

As the vehicle moves forwardly, the roller 54 rides up on the ramp bar 16. This elevates the slide 53 and carries the head 50 away from the plunger 44, thus freeing the spring 45 and releasing the valve. If the ramp is in the position shown in full line in Fig. 1, the valve remains unseated, and the brake is applied or the danger signal given. If the ramp is in safety position shown in dotted lines in Fig. 1, the slide 53 is elevated to open the air valve, and has an additional idle elevation. In this case, however, the ramp is high enough to engage the roller 70 of a resetting slide 71. When this slide is elevated, a pawl 72 carried thereby engages the arm 73 of a four-armed lever pivoted at 74. One of the arms 75 of this lever depends and loosely yokes around the plunger 44, and the swinging of this arm toward the left by the elevation of the slide 71 causes the arm to act on the pin 47 projecting from the plunger 44, and move the plunger to the left and reseat the valve. Accordingly, whenever the ramp is in the elevated position as shown in dotted lines in Fig. 1, not only is the valve opened but it is immediately reset, so that no danger indication is given.

It is to be understood that the parts described are mounted in a suitable casing, secured at some suitable point on the vehicle. This casing is shown in Figs. 2 and 3 as a rectangular box, open at the bottom, and having a vertical inner wall 80 and an outer wall 81. The valve casing is secured to these walls as illustrated by the screws 82 in Fig. 2. The slides mentioned extend practically from one wall to the other, and are slidably guided thereby. Thus, slide 53 has projecting studs 57, occupying vertical grooves 84 in the walls 80 and 81, and the journal pin 58 for the roller 54 projects at its ends into grooves 85 in the walls. Similarly, the journal pin 77 for the roller 70 occupies grooves 86 in the walls, and the slide 71 has near its upper end studs 78 occupying vertical grooves 87. The pawl 72, carried by the slide 71, occupies a recess 79 in this pawl, and is normally pressed into active position by a spring 76 behind the pawl. The spring 60, which acts to press downwardly on the slide 53, presses upwardly at its upper end on the arm 61 of the four-armed lever 73, so that one spring may act for both the slide and the four-armed lever.

The mechanism described is effective to apply the brake or give a danger indication whenever the ramp is in the normal or danger position; it is also effective to prevent such application when the ramp is in the elevated or safety position. For very

high speeds, however, it might result that the resetting slide would act upwardly and seat the valve, and then clear the ramp before the slide 53 had been depressed to bring the abutment 50 in front of the plunger 44, 70 should there be any sticking of the slide 53, or its inertia be too great. To provide for this contingency, I equip the device with a time latch, which acts on the arm 75 to hold it temporarily in position with the 75 valve closed until the slide 53 shall have ample time to return. This latch is shown in Fig. 2. It consists of a dog 90, provided with a shoulder 91, adapted to engage the lower end of the arm 75, the dog being pivoted to an intermediately pivoted lever 92, the lower end of which is connected by a link 94 with a plunger 95 in a cylinder 96. This cylinder carries some non-freezing oil. The dog is given a tendency to move upwardly by a spring 97, but is normally held in idle position by a lug 98 on the lever 51. When the slide 53 rises, the dog 90 is freed, and then as soon as the resetting bar swings the lever 75 toward the left to reset the 90 valve, the shoulder 91 springs upwardly in front of that lever and prevents its immediate return. The tendency of the lever to return under the action of the spring 60 moves the dog toward the right. This 95 movement, however, is retarded by the oil in the cylinder 96. This oil, gradually leaking past the piston 95, allows the lever 75 to gradually return to normal position, but before this has happened (within a second or two) the slide 53 will have descended to normal position, and as it comes into that position, its lug 98 will abut the dog 90, and return it to normal position, freeing the arm 75. As the head 50 must be in the path 100 of the plunger 44 before the lug 98 can engage the dog 90, the valve is effectively held seated. If, however, there should be any undue delay in the return of the slide 53, for example, by reason of the breaking of 110 the spring 60, the latch 90 will soon release the lever 75, releasing the valve, and the brake will be applied.

The combination of a time latch with resetting mechanism is shown, described and 115 claimed broadly in an application of mine filed September 18, 1913, and number 790,392.

If the roller 54 which engages the ramp should accidentally be broken, this will remove the stop for the roller 56, and the upper portion of the lever 51 will be allowed to move into the recess 55 in the slide 53, and will do so under the action of the spring 45, thereby opening the valve and giving the 125 danger indication.

The portion so far described has been concerned with the forward running of the vehicle. As it is not desired to give a danger indication on backward running, I pro- 136

- vide mechanism to invariably reseat the valve for such backward movement, after it has been opened by the slide 53, traveling across the ramp. This mechanism consists 5 of a slide 100, vertically guided in a manner similar to the guiding of the slide 71, and carrying a roller 101, designed to co-act with the ramp bar 18 in its normal or its elevated position. The slide 100 carries a pawl 102, 10 adapted to co-act with the lever 103, pivotally mounted at 104, and connected by a link 105 with an arm 106 of the four-armed lever 73. Accordingly, on backward running, the opening of the valve by the slide 53 is immediately followed by its closure by the slide 100 acting through the mechanism mentioned to force the plunger toward the left.

It should be noted that the vehicle mechanism described is so arranged that in case of any breakage, the valve is opened, resulting in a danger application. Accordingly, whenever the engineer passes a ramp and receives no danger application, he is advised that the mechanism is in proper working order.

To provide against the contingency of the system being rendered non-effective by reason of some obstruction on the train depressing the ramp, and the same being jammed so that it stays down, I provide a circuit controller, operated by the plunger 24, which is designed to throw the adjoining signals to danger. Such circuit controller is shown, 25 described and claimed broadly in my Patent No. 1,129,202, issued February 23, 1915, and as there shown, operates to short circuit a controlling relay and also open the battery therefor. Fig. 1 shows such an arrangement of contacts, wherein 111 and 112 are terminals of the short circuiting line for the relay, these terminals being normally out of contact, but pressed into contact when the plunger 24 is depressed by 30 reason of the arm 113 thereon, which by this movement rides out of a depression in the terminal 111. 115 and 116 are terminals of the battery line which are bridged by an arm 117, carried by the plunger 24. Accordingly, the movement of the plunger removing this bridge opens the battery circuit. This short circuiting and opening of the lines may be effective to cause danger indications at an adjacent signal or signals, 35 thus showing in advance that a certain ramp is out of order.

I claim:

1. The combination with vehicle mechanism for initiating a danger indication and 40 mechanism for counteracting such indication before it becomes effective, of a device for normally acting on the initiating mechanism and clearing the counter-acting mechanism, said device being movable into position where it acts on both mechanisms.

2. The combination with a vehicle device adapted to initiate the application of a danger indication, and a vehicle device to prevent such application being effective, of a normally stationary ramp, adapted to normally engage the initiating mechanism and clear the preventing mechanism, and means for moving said ramp into position where it engages both mechanisms. 70

3. The combination with an air valve on 75 a moving vehicle of a movable member that will open the same, a movable member adapted to close the same, a ramp normally acting on the opening mechanism and clearing the closing mechanism, and means for 80 moving said ramp into position where it acts on both mechanisms.

4. The combination with applying and counter-acting means on a vehicle of a ramp composed of a pair of bars hinged together, 85 means holding said ramp normally stationary and in the path of the applying means, and means for swinging one of the bars to change the peak of the ramp and bring it into the path of the counteracting means. 90

5. The combination with initiating and counteracting means on a vehicle of a ramp for operating the same, said ramp being normally stationary and clearing the counteracting means but engaging the applying 95 means, means for moving the ramp into a position to engage both means, and means for enabling the ramp to be displaced by an obstruction on the vehicle, and to automatically return to position thereafter. 100

6. The combination with a pair of hinged bars constituting a ramp of means for holding them normally stationary, and means for raising them to change the peak of the ramp, and means whereby they may be moved in 105 the opposite direction to clear an obstruction.

7. The combination of a pair of hinged bars constituting a ramp, means for holding them normally stationary in an intermediate position, means for moving them to raise the peak, and a suitable signal connected therewith, and concurrently changed by such movement. 110

8. The combination of means constituting 115 a ramp, means for moving the same in one direction to change the peak of the ramp, means whereby the ramp may be moved in another direction to clear an obstruction and automatically return, and means whereby 120 such clearing movement varies an electric circuit.

9. The combination with brake applying mechanism and mechanism adapted to prevent the application being effective on a 125 vehicle of a ground device adapted to co-act therewith, and consisting of a normally stationary ramp acting on the applying mechanism, said ramp being movable into position where it acts on both mechanisms, said 130

- ramp being also movable into position where it will clear an obstruction, means for automatically returning the ramp when moved into the latter position, and means for controlling an electric circuit by such movement.
10. The combination with brake-applying and preventing means on a vehicle of a normally stationary ramp, adapted to co-act with the applying means, and movable to a position where it may co-act with both means, and a signal connected with the ramp and automatically moved to safety when the ramp is moved into position to co-act with both of said means.
11. The combination with a normally stationary ramp adapted to be elevated, of an air valve on a vehicle, means thereon adapted to engage the ramp and move a variable distance according to the position of the ramp, but always open the air valve, and means on the vehicle engaging the ramp only when elevated and operating to reset the valve.
12. The combination with a ramp of a vehicle mechanism having a slide carrying a roller to engage the ramp, an air valve releasable by the movement of said slide, a second slide carrying a roller for ramp engagement, and mechanism operated by the second slide to reset the valve.
13. The combination of an air valve, a plunger therefor, a slide carrying an abutment for the plunger, the slide being movable to release the plunger, a second slide and a lever operated thereby and adapted to engage the plunger to reset it.
14. The combination with a valve seat of a plunger therefor, a slide having an abutment for the plunger, a second slide, a lever adapted to be acted on by the second slide and engage the plunger to reset the valve, and a spring between the first slide and lever.
15. The combination with an air valve and plunger therefor of an operating slide, an abutment thereon for the plunger, movable by the slide out of the path of the plunger to release the valve, and means for resetting such valve, and a time latch for holding the resetting mechanism to allow the abutment time to return.
16. The combination of a valve having a plunger, an operating slide having an abutment for the plunger, a resetting slide, a lever therefor operating on the plunger, a time latch for the lever, and means on the slide first mentioned for releasing the latch when the abutment returns to normal position.
17. The combination with an air valve of an operating slide having a roller, an abutment for the air valve carried by the slide, and a stop for the abutment acting against said roller.
18. The combination of a valve casing, a plunger therefor, an operating slide having a roller, a lever pivoted on the slide and presenting an abutment for the plunger, the lever being normally held in position by engagement with said roller whereby the breaking of the roller releases the valve.
19. The combination of a valve, an operating slide adapted to release the same, two resetting slides, and mechanism controlled by said last mentioned slides for resetting the valve, one slide being at the rear of the operating slide and the other in advance thereof.
20. The combination with a normally stationary ramp, adapted to be moved, of a vehicle mechanism having a valve, an operating slide adapted to release the valve and positioned to engage the ramp, whether in normal position or moved, a resetting slide in advance of the main slide adapted to engage the ramp, whether in normal position or moved, and a resetting slide at the rear of the main slide, engaging the ramp only when moved.
21. The combination with a valve casing of a plunger therefor, a movable member adapted to release the plunger, a lever having an arm adapted to engage the plunger to reset it, a resetting device adapted to act on another arm of said lever, and a second resetting device adapted to act on another arm of said lever, said resetting devices being one in advance of the operating member and the other at the rear thereof.
22. The combination with a pair of hinged bars constituting a ramp, of means for holding them normally stationary in an intermediate position forming a peak, means for moving them to raise the peak, and means whereby they may be lowered to clear an obstruction and automatically return to the intermediate position.
23. The combination of means on a vehicle for initiating a danger indication, means on the vehicle for preventing such indication, a ramp having an adjustable peak adapted to act on both means on the vehicle or only one means according to conditions of safety or danger.
24. The combination with means on a vehicle for initiating a danger indication, means for counteracting such indication, a ramp adjacent the trackway adapted when in one position to give a danger indication and adapted to be raised to a position where it engages the counteracting means to give a safety indication.
25. The combination with a vehicle device adapted to apply a danger indication and a vehicle device adapted to prevent such application, of a device for normally acting on the applying mechanism and clearing the preventing mechanism, said device being movable into position where it acts on both mechanisms.

26. The combination, with control applying means on a vehicle and means on said vehicle preventing the application being effective, of a ramp having an adjustable peak 5 adapted to act on both vehicle means or on only one of the vehicle means according to conditions of safety or danger.

27. The combination, with means on a vehicle for applying a brake and means on 10 the vehicle for preventing such application, of a ramp having an adjustable peak, means holding said ramp normally stationary and in the path of the applying means, and means for changing the peak of the ramp to 15 bring it into the path of the preventing means.

28. The combination, with means on a vehicle for applying a brake and means on the vehicle for preventing such application, 20 of a ramp composed of a pair of bars hinged

together, means holding said ramp normally stationary and in the path of the applying means, and means for moving one of the bars to change the peak of the ramp and bring it into the path of the preventing 25 means.

29. The combination, with means on a vehicle for applying a brake and means on the vehicle for preventing an application of the brake; of a controllable track fixture adapted to act on both vehicle means or on only one of the vehicle means according to the position of said fixture. 30

In testimony whereof, I hereunto affix my signature in the presence of two witnesses. 35
